UNITED STATES PATENT OFFICE

2,437,942

PAD SUPPORT FOR SHOE PRESSES

Ernest Dunford, St. Louis, Mo., assignor to Landis Machine Company, St. Louis, Mo.

Application December 23, 1946, Serial No. 717,946

6 Claims. (Cl. 12—33)

1

The invention relates to shoe presses such as are commonly used in cementing a shoe sole or half sole to the shoe upper and the invention consists in an adjustable shoe support for such presses adapted to cooperate with a last and other associated parts whereby pressure is applied to the shoe upper and to the adjacent face of the shoe sole.

The main object of the invention is to equalize the pressure throughout the area of the shoe parts to be cemented together.

The invention is particularly intended for use in shoe-repair shops where successive operations may be made upon shoes of substantially different heel heights with corresponding variations in the angle between the shank and the forward portion of the sole, and it is a further object to provide a readily adjustable shoe support which will accommodate variations in the angle mentioned and without requiring the operator to use a number of shoe supports to meet different conditions. In the manufacture of shoes, where large quantities of each shoe size and style may be made at one time, it is practical to have a separate support for each height of heel but this would be an impractical expense for the shoe repairman.

These and other detail objects are attained by the structure illustrated in the accompanying drawings, in which:

Figure 1 is a side elevation of a shoe press equipped with a support constructed according to the present invention and mounting a deformable cushion.

Figure 2 is a top view of the rear portion of the support for the cushion and drawn to enlarged scale.

Figure 3 is a partial end view and transverse vertical section taken approximately on the line 3—3 of Figure 2.

Figure 4 is a vertical longitudinal section taken approximately on the line 4—4 of Figure 2 and indicating the support adapted to a shoe having a low heel.

Figure 5 is a section similar to Figure 4 showing the support adapted to a shoe having a higher heel than that of Figure 4.

The shoe press shown in Figure 1 corresponds generally to that illustrated in Patent No. 2,268,874, issued to C. L. Huntoon, January 6, 1942, and includes a frame 1, a crank wheel 2 journaled thereon, rods 3 connecting the wheel crank pin 4 and a pivoting yoke 5 having a bayonet joint engagement with the end of an arm 6 of a last which may be inserted within the shoe S. The

2

last may correspond to that illustrated in Patent No. 2,302,220, issued to C. L. Huntoon, November 17, 1942.

Frame 1 mounts a support 7 preferably comprising a rigid tray-like main member 7a and an adjustable segment 7b. Member 7a has a peripheral upstanding wall 7c having a gap adjacent the rear end of the member. The support mounts a deformable cushion 8 confined by wall 7c and upon which the bottom of the shoe may rest. Crank wheel 2 has a toothed periphery, and a shaft 9 journaled in frame 1 has a worm 10 in mesh with the teeth of wheel 2 and has a handle wheel 11 by which the shaft and wheel 2 may be rotated to draw rods 3 downwardly and thereby apply pressure through the last to the interior of the bottom of the shoe and to thrust the shoe sole against the deformable cushion 8. The general construction of the press corresponds to that disclosed in the above mentioned patents and does not, in itself, constitute the present invention.

Segment 7b is relatively small as compared to member 7a and is arranged for vertical adjustment relative to the member to vary the height of the support beneath the cushion at the shoe shank. When shoes with relatively low heels are operated upon, the segment is lowered relative to the member, as shown in Figure 4, and when shoes having relatively high heels are operated upon, the segment is raised relative to the member, as shown in Figure 5.

Segment 7b is positioned at the rear of member 7a in a recess 8a in cushion 8 and extends laterally across the gap in wall 7c. Segment 7b has a depending pin 13 near each of its ends slidably received in bearings 14 in rearwardly extending lugs 15 on member 7a. Brackets 16 depend from the underside of member 7a and rotatably support a shaft 17 mounting a pair of cams 18 arranged to engage pins 13. As shaft 17 and cams 18 are rotated by a handle 19, pins 13 slide vertically in bearings 14 and segment 7b is raised or lowered relative to member 7a. Each cam 18 has a series of indentations 20 in its periphery to receive the end of the corresponding pin 13 to hold segment 7b in adjusted position.

Screws 21 are threaded into pins 13 at their lower ends after segment 7b is assembled to member 7a to prevent accidental disassembly of segment 7b from member 7a.

Segment 7b is readily adjustable relative to member 7a to adapt the support for shoes having shanks at different angles to the soles, i. e., for shoes with different heights of heels. When the

press is operated, the cushion will be distorted to equalize the pressure throughout the area of the shoe parts to be cemented together. The rear end of the cushion, not being confined by an up-standing wall as is the rest of the cushion, will be distorted upwardly and rearwardly of segment 1a and will be opposed by the breast of the shoe heel and will fill the angle between the shank and the heel to apply pressure to the extreme rear end of the shank comparable to the pressure applied to other portions of the sole.

The details of the construction may be varied according to the invention, and the exclusive use of those modifications coming within the scope of the claims is contemplated.

What is claimed is:

1. A shoe press pad support comprising a member adapted to receive a deformable cushion, a relatively narrow elongated cushion engaging segment having a depending pin slidably mounted in one end portion of said member, and a rotatable cam to adjust said segment relative to said member and having a series of indentations in its periphery to receive said pin to hold said segment in adjusted position.

2. A shoe press pad support comprising a rigid tray-like member adapted to receive a deformable cushion, a relatively small segment at the rear of said member and having a depending pin slidably in said member, and a rotatable cam in engagement with said pin to adjust said segment relative to said member to vary the support of a restricted portion of the cushion mounted on the member.

3. In a shoe press pad support, a rigid tray-like member adapted to receive a deformable cushion, an elongated relatively small segment at the rear of said member, said segment being positioned with its longitudinal axis extending substantially transversely of said member and having a depending pin near each of its ends slidable vertically in said member, a rotatable cam in engagement with each of said pins and arranged to adjust said segment vertically relative to said member, and a handle for rotating both of said cams.

4. In a shoe press pad support, a rigid tray-like member adapted to receive a deformable cushion, an elongated relatively small segment at the rear of said member, said segment being positioned with its longitudinal axis extending substantially transversely of said member and having a depending pin near each of its ends slidable vertically in said member, a bracket depending from the bottom of said member, a shaft rotatably mounted on said bracket, cams mounted on said shaft and rotatable therewith, said cams engaging said pins and being arranged to adjust said segment vertically relative to said member.

5. In a shoe press for applying a shoe sole to a heeled shoe, a shoe support comprising a rigid tray-like member having a peripheral upstanding wall, a deformable rubber pad positioned on said member and confined by said wall, there being a gap in said wall adjacent the rear end of the pad, an elongated relatively narrow pad-supporting segment extending laterally across said gap and movable vertically relative to said member, the rear portion of said pad having a recess in its bottom receiving said segment and said portion extending over the top of said segment so as to be opposed by the breast of the heel of a shoe mounted on the pad.

6. A shoe press pad support comprising a member adapted to receive a deformable cushion, a relatively small cushion adjusting segment including a pin slidably mounted in one end of said member to guide said segment in its movement relative to said member, and a cam operatively connected to said segment to adjust said segment relative to said member.
